UNITED STATES PATENT OFFICE.

EDWIN F. JONES AND JOHN A. AULD, OF ERIE, PENNSYLVANIA.

MATERIAL-HANDLING APPARATUS.

Application filed March 31, 1923. Serial No. 629,069.

This invention is designed to handle material, particularly such as road-way material as crushed stone and gravel. Where this is used it is necessary to measure out a predetermined quantity of crushed stone and gravel, usually these measured quantities being dropped into the vehicle together so as to make what is ordinarily called a batch. In carrying out the invention there is a storage bin with a hopper bottom adapted to carry the materials below these measuring bins sufficiently high to permit the passage of the vehicle below them to receive the material. Difficulty has been heretofore experienced in striking off or cutting off the measured material without waste of the material, in other words, striking off the material in such a way as to prevent the spilling of any excess material, or the locking of the cutting off or striking off device. Where crushed stone is used it is particularly difficult to accomplish this in that the units of stone are of sufficient size to prevent an accurate fit of the closing gates. Other details and features of the invention will appear from the specification and claims.

The invention is illustrated in the accompanying drawings as follows:—

Fig. 1 shows a side elevation of the device.

Fig. 2 an end view.

Fig. 3 a plan view of the striking off device.

Fig. 4 a central section through the measuring bins and striking off mechanism.

Fig. 5 an enlarged view of the measuring bins and the devices carrying the strike-off mechanism.

1 marks the supporting posts. These are connected by cross beams 2 and 3 and by longitudinal beams 4, 5 and 6, with a proper brace 7 bearing in mind the desirability of having the vehicle pass below the bins. 8 indicates the gravel bin and 9 the crushed stone bin. These bins are provided with openings 10 and 11 which are connected by spouts with the measuring bins or boxes 12 and 13. The bottoms of the bins are flanged at 14 and angle braces 15 extend across these. The bin carrying beams 16 are secured below the bins on the angle plates 15 and rods 17 extend from the beams 16 to ears 18^a on the boxes, the lower end of the boxes being telescopically formed so that by adjusting these rods the capacity of the measuring bins may be altered. The supporting beams

16 are connected by short cross beams 18 and angle irons 19 are mounted on the cross beams 18 parallel to the beams 16. Rollers 20 are journaled between the beams 19 and 16 and carry the gate plate 21. Angle irons 22 are arranged along the sides of the gate plate so that the plate is stiffened over the rollers and designed to carry the load upon it. The gate plate has the apertures or openings 23 which are adapted to be brought into register with the openings 10. A bracket 24 is secured to the end of the angle irons 22 and links 25 and 26 extend from these brackets to a hand lever 27 by which the gate may be operated. The lever is pivoted at 28 on a bar secured to the beam 29 on the bottom of the hopper.

Spouts or enclosures 30 surround the openings 10 and 11 down as far as the gate plate. This is open at 31, or toward the closure side of the gate so that when the gate plate is thrust toward the closing movement there is a clearance through the opening 31 which prevents the blocking of the movement by the crushed stone, the opening being larger than the units of the material that is being used.

In order to prevent the spilling of material which is struck off in this way we provide a means which catches the material as the gate closes and as the gate is again opened spills the material into the measuring bin. In the specific structure shown an apron 32 is pivoted at 33 and rests when in an outward position on the stop bar 34. This apron extends through the aperture 23 so that as the gate is opened the apron is engaged by the rear wall of the aperture and swung up to a vertical position. It will be understood that as the opening 23 moves along the apron any material above the gate that is not carried by the gate slides down the measuring device so that with each operation there is a deposit of any excess material that may be carried out in the striking off apparatus through the measuring box or bin.

Gates 35 are supplied at the bottom ends of the measuring boxes in the usual manner. These gates 35 are carried by angle irons 36, the angle irons 36 having rollers 37 operating on tracks 38 on the bottoms of the bins. Bars 39 extend along the bars 38 connecting the gates of two of the measuring bins. These bars are connected by links 40 with operating levers 41 so that they may be opened when desired.

It will be understood that the measuring boxes 12 and 13 operate in pairs and that several pairs of these may be arranged side by side so as to put a number of batches into different compartments of a vehicle for transferring the material.

What we claim as new is:—

1. In a material handling apparatus, the combination of a measuring bin; a strike off device operating over the bin; and a catcher at the side of the bin on which material carried over by the strike off device is deposited, said catcher delivering material caught to the bin.
- 15 2. In a material handling apparatus, the combination of a stationary measuring bin; a strike off plate above the bin; and a catcher at the side of the bin on which material carried over by the strike off device is deposited, said catcher delivering the same to the bin.
- 25 3. In a material handling apparatus, the combination of a stationary measuring bin; a strike off plate above the bin; and a catcher at the side of the bin on which material carried over by the strike off device is deposited, said catcher delivering the same to the bin and comprising a tilting apron.
- 30 4. In a material handling apparatus, the combination of a stationary measuring bin; a strike off plate above the bin, said strike off plate having an aperture therethrough; and a catcher at the side of the bin comprising a tilting apron extending through the aperture and tilted as the plate is moved and delivering the material carried over by the strike off plate to the bin.
- 35 5. In a material handling apparatus, the combination of a storage bin; a measuring bin arranged under the storage bin; a spout connecting said measuring bin; a strike off plate operating through said spout, said

spout having an opening at the closing side of the strike off plate; and an apron at the side of the opening adapted to receive material carried over by the strike off plate and to deliver the material carried through the opening to the measuring bin.

45 6. In a material handling apparatus, the combination of a storage bin; a measuring bin arranged under the storage bin; a spout connecting said measuring bin; a strike off plate operating through said spout, said spout having an opening at the closing side of the strike off plate; and a tilting apron 50 at the side of the opening actuated by the plate and receiving and delivering material carried over by the plate to the measuring bin.

55 7. In a material handling apparatus, the combination of a pair of storage bins; a pair of measuring bins; spouts connecting said bins; a strike off plate operating under said spouts, said plate having apertures adapted to be brought into and out of register with the spouts, said spouts having an opening at the closing side; and tilting aprons at the sides of said openings extending through the strike off plate, said tilting aprons being actuated by the plate and returning the 60 material passing through the openings to the measuring bins.

70 8. In a material handling apparatus, the combination of a storage bin; a spout leading from the bin; beams carried below the 75 bin; cross beams connecting the first-mentioned beams; inside beams connecting the cross beams; rollers between the inside beams and the first-mentioned beams; and a closure gate operating on said rollers.

80 In testimony whereof we have hereunto set our hands.

EDWIN F. JONES.
JOHN A. AULD.
